UNITED STATES PATENT OFFICE

RUDOLF POPP, OF VALPARAISO, INDIANA, ASSIGNEE TO MCGILL MANUFACTURING COMPANY, A CORPORATION OF INDIANA

SWITCH OPERATING MECHANISM

Application filed June 8, 1933. Serial No. 368,005.

My invention relates to switch operating mechanism, and more particularly to such mechanism for lamp socket switches adapted for use in candle-type sockets and the like.

The principal purpose of this invention is to provide a simple and novel means for operating the switch mechanism from a rotating stem.

It is also a purpose of this invention to provide means for rotating a switch contact member, which means shall also form the sole support for said member.

It is also a purpose of this invention to provide, in a device of this character, means for supporting the movable switch elements which permits of the rapid assembly of these elements in their proper positions.

Other objects and advantages of the invention will appear as the description proceeds in connection with the accompanying drawings. However, it is to be understood that the description and drawings are illustrative only, and are not to be taken as limiting the invention except in so far as it is limited by the claims.

In the drawings,—

Fig. 1 is a side view of a lamp socket unit with my improved switch mechanism therein;

Fig. 2 is a top plan view of the device shown in Fig. 1;

Fig. 3 is a side view taken at right angles to Fig. 1;

Fig. 4 is a section on the line 4—4 of Fig. 3, with certain of the elements left in full position for the purpose of more clear illustration;

Fig. 5 is a section on the line 5—5 of Fig. 3;

Fig. 6 is a section on the line 6—6 of Fig. 1;

Fig. 7 is a vertical section through the movable element of the switch mechanism and its mounting; and

Fig. 8 is a section on the line 8—8 of Fig. 5, showing only the bridging contact member of the switch.

Referring now in detail to the drawings, I show at 10 a lamp socket or shell of the usual screw-threaded type, which socket has a depending ear 11 passing through a slot in an insulating washer or disk 12, which disk is also cut away at 13 for a purpose which will presently appear.

Within the socket 10 there is provided a substantially horseshoe-shaped clamping member 14 which has depending ears 15 and 16 extending through the disk 12 and engaging on the outer sides of a pair of spaced insulating plates 17 and 18. These plates are held spaced by spacing elements 19 and 20, which elements carry also a pair of spring contacts 21 and 22. The element 19 has a portion 23 which extends upwardly through the slot 13 of disk 12 and forms a central contact for the lamp which is to be inserted in the socket 10.

Plates 17 and 18 are also spaced at their lower ends by means of a base or mounting member 24 which has a depending screw-threaded portion 25 that may be suitably attached to the supporting housing for the socket. Since the supporting housing forms no part of the present invention, further description thereof will not be made.

The base 24 and the portion 25 have a bore 26 in which the shaft 27 is mounted, this shaft 27 being held against downward movement by a suitable collar 28 upon which the shoulders at 29 of the flattened portion 30, formed integral with the shaft 27, bear. At the lower end of this shaft, it is provided with a suitable handle 31, which may be secured thereto, as by means of a set screw 32.

The flat portion 30 has secured on opposite sides thereof a pair of spring members 33 and 34, which members have their upper ends formed on a spiral in cross section, as shown more clearly in Fig. 6, and these upper ends are spaced somewhat from the portion 30. The portion 30 is also narrowed or formed with shoulders at 35 and 36, and an insulat-

ing member 37 rests upon these shoulders, this insulating member being provided with a bridging contact 38 which extends substantially diametrically across the member and has contact faces 39 and 40 overlying the 5 opposite pair of ratchet teeth which are provided on the member 37, the ratchet teeth intermediate this pair being devoid of any metallic contact thereon, so that when the 10 spring contacts 21 and 22 rest upon them the circuit is broken between these contacts. It is obvious, of course, that when contacts 21 and 22 engage the faces 39 and 40 an electric circuit is completed through these contacts.

15 A suitable washer or head 41 is mounted on the top of the member 30 so as to hold the member 37 thereon, but permits its rotation relative to the member 30 at any time. The member 37 is, as shown in Fig. 8, and also in Fig. 6, provided with internal ratchet 20 teeth at 42, with which the spring members 33 and 34 engage.

Now, the action of the switch is as follows:

Assuming that it is desired to turn the bridging member 38 from the position shown 25 in Fig. 6, in which no contact is established between the fingers 21 and 22, into a position establishing contact between these fingers, the stem 31 is rotated in a direction to cause the members 33 and 34 to engage the steep 30 faces, such as 43 and 44, of the internal ratchet 42, and thus cause the member 37 to rotate. The rotation of this member moves the contact faces 39 and 40 into engagement 35 with the contacts 21 and 22, and, owing to the spring-like character of the fingers 21 and 22, they snap into contact with the faces 39 and 40. However, if the stem 31 is rotated in the opposite direction, the shape of 40 the members 33 and 34 and the shape of the ratchet teeth, readily permit a sliding action of the members 33 and 34 relative to the member 37, and the engagement of the free 45 ends of the members 21 and 22 with the adjacent shoulders on the outer ratchet teeth of the member 37 effectively prevents the member 37 from being turned in the wrong direction.

Thus it will be clear that rotation of member 31 in one direction will give a step-by-step making and breaking action for the switch, while the rotation of the handle 31 in the opposite direction will not disturb the position of the member 37 relative to the 55 spring contacts 21 and 22.

The spacing member 20 is provided with one wiring terminal, as shown by the screw 45, and the other terminal of the circuit is preferably connected to the screw 46, which 60 holds the ears 11, 15 and 16 against the outer sides of the pieces 17 and 18.

From the above description, it will be seen 65 that I have provided a very simple construction, including a switch mechanism for lamp sockets, which mechanism is of comparative-

ly strong and rugged construction, so that the same may have a long life. There being but very few parts, which are readily assembled, this device is one which requires but little expense in assembling, and thus can be produced at a comparatively low cost.

Having thus described my invention, what I claim as new and desire to secure by Letters Patent is:

1. In a switch, stationary contacts, a body 75 of insulating material between said contacts having a bridging contact thereon adapted in one position of said body to electrically connect said stationary contacts, a rotatable stem upon which said body is rotatably mounted, and interengaging means on said body and stem for causing said body to move with said stem in one direction of rotation and causing said stem to rotate independently of said body in the other direction.

2. In a switch, stationary contacts, a body 80 of insulating material between said contacts having a bridging contact thereon adapted in one position of said body to electrically connect said stationary contacts, a rotatable stem upon which said body is rotatably mounted, and means on said body and stem for causing said body to move with said stem in one direction of rotation, said means including internal ratchet teeth in said body 85 and spring fingers on said stem engaging said teeth, said fingers being spirally curved in cross section where they extend into said body.

3. In a combined switch and lamp socket, a 90 socket shell, insulating supporting plates therefor, means holding said plates in spaced relation including spaced metallic elements one of said elements carrying a center socket contact extending into said shell, said elements having spring contacts thereon, a bridging contact member interposed between said contacts, and a rotatable stem carrying said bridging contact member, said stem being rotatable relative to said bridging contact member in one direction.

4. In a device of the character described, a 95 frame, a plurality of stationary contacts mounted thereon, a bridging contact element interposed between said contacts, an operating stem rotatably mounted in said frame, an insulating body upon which said element is mounted, said body having an opening in which a portion of said stem is rotatably and non-slidably mounted, and cooperating 100 means on said stem and body whereby to rotate said body only when said stem is turned in one direction, said stem being rotatable independently of said body when said stem is turned in the opposite direction.

5. In a switch, a frame, stationary contacts 105 mounted thereon, a body of insulating material between said contacts having a bridging contact thereon adapted in one position of said body to electrically connect said station-

ary contacts, a rotatable stem rotatably mounted in said frame, said body being rotatably and non-slidably mounted upon a portion of said stem, and means on said body and stem to cause said body to move with the stem only in one direction of rotation, said means including internal shoulders on said body and resilient means on said stem engaging therewith.

10 In witness whereof, I hereunto subscribe my name this 15th day of May, A. D., 1929.
RUDOLF POPP.
